WORK GUIDING AND FEEDING ATTACHMENT FOR BAND SAWS

Hans Petersen, Minneapolis, Minn., assignor to
 Continental Machines, Incorporated, Minneapolis, Minn., a corporation of Minnesota

Application May 31, 1943, Serial No. 489,165

4 Claims. (Cl. 29—68)

This invention relates to band saws and refers particularly to a work feeding and guiding attachment especially adapted for use with metal cutting band saws.

It is an object of this invention to provide an attachment which may be quickly attached to the work supporting table of a band saw and by which various types of work and particularly mitering operations are facilitated.

Another object of this invention is to provide an attachment of the character described incorporating a manual feed which may be quickly and easily disengaged to permit the use of the power feed with which metal cutting band saws are generally equipped or to permit quick adjustment of the work engaging guide or miter bar.

Another object of this invention is to provide an attachment of the character described wherein the feed screw and the means for guiding the work feeding motion are so related as to preclude binding of the parts and insure smooth feeding of the work.

Another object of this invention is to provide an attachment of the character described which may be quickly set up to enable accurate ripping and cutting off in addition to mitering operations.

Still another object of this invention is to provide an attachment of the character described which is rugged and well adapted for the purpose for which it is intended.

With the above and other objects in view which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawings illustrate one complete example of the physical embodiment of the invention constructed in accordance with the best mode so far devised for the practical application of the principles thereof, and in which:

Figure 1 is a perspective view illustrating the use of the attachment of this invention for cutting off stock and using the power feed of the machine;

Figure 2 is a perspective view of the attachment illustrating the manner in which it is used in mitering operations;

Figure 3 is a fragmentary plan view illustrating

the way in which the attachment is used for ripping;

Figure 4 is an enlarged plan view of the entire attachment with parts broken away and in section;

Figure 5 is a side view of the attachment in position on the work supporting table of a band saw;

Figure 6 is a detail cross sectional view taken through Figure 5 on the plane of the line 6—6;

Figure 7 is a detail cross sectional view taken through Figure 4 on the plane of the line 7—7 and illustrating the manner in which the attachment is adjustably secured to the work supporting table of the band saw; and

Figure 8 is a detail cross sectional view taken through Figure 5 on the plane of the line 8—8.

Referring now more particularly to the accompanying drawings, in which like numerals indicate like parts, the numeral 5 designates the work supporting table of a conventional metal cutting band saw equipped with the customary saw band 6 which is guided to travel vertically through the table 5.

25 The attachment of the invention indicated generally by the numeral 7 is adapted to be detachably and adjustably secured to the work supporting table 5. The main support for the attachment comprises a bracket 8 provided with a slideway 9 to receive a slide 10 fixed to the front edge of the work supporting table. Clamping screws 11 are provided to releasably secure the bracket in any position of adjustment along the slide 10.

30 35 The bracket 9 has two parallel spaced slide-ways 12 mounted thereon and bored to receive rods 13. At their outer ends the rods 13 are rigidly connected by a cross bar 14 anchored to the ends of the rods as in any suitable manner. The 40 opposite or inner ends of the rods 13 are secured in depending bosses 15 on the bottom of a miter head base 16. The rods 13 are thus rigidly connected by the miter head base 16 and the cross bar 14 and together these parts form a rigid 45 frame-like structure slidably mounted on the bracket.

Rotatable on the miter head base 16 is a miter head 17 and rising above the miter head is a power feed chain collar 18. A screw 19 threaded in the base 16 holds the miter head and collar assembled with the base and locks the miter head in any desired position of adjustment, such adjustment being facilitated by a scale 20 on the base and a gauge mark (not shown) on the front 50 of the miter head.

The miter head has an arm 21 extending radially therefrom to which a miter bar support 22 is secured. This miter bar support has a miter bar or other work engaging member 23 secured thereto and which when in use for mitering has a work stop 24 fixed thereto to support the end of the work as will be readily apparent.

In order to support the miter head base and the assembly carried thereby for free movement across the face of the work table, a slide pin or foot 25 is secured in the under face of a boss 26 on the bottom of the base 16 between the bosses 15.

When the attachment is to be used for ripping, the miter head is adjusted to its position at which the miter bar 23 forms a ripping fence parallel with the rods 13 as clearly shown in Figure 3. When used for this purpose the work stop 24 is of course removed to enable the work to be fed through.

For mitering and cut offs a work feed is provided. This may be accomplished manually by means of hand wheel 27 or through use of the power feed with which the machine is equipped. The power feed forms no part of the present invention, but for purposes of illustration includes a chain 28 or other tension member adapted to wrap around the work or the work guide and to exert a pull thereon. In the present case when the power feed is used the chain is engaged over the collar 18.

The hand wheel 27 is fixed to a feed screw 29 having its ends journaled in bearings carried by the cross bar 14 and the miter head base 16. A nut 30 mounted on the bracket 8 actively engages the feed screw when it is desired to use the manual feed.

The nut 30, as best shown in Figure 6, comprises two half sections 31 extending up from bosses 32. The bosses 32 have flanges 33 extending in opposite directions therefrom to be slidably received in guideways 34 in the underside of two depending portions of the bracket as best shown in Figure 5. A shaft 35 extends through the bosses 32 and has stop collars 36 and 37 fixed to its opposite ends the former being provided with a handle 38.

The meeting faces of the stop collars 36-37 and the adjacent ends of the bosses are formed with interengageable V projections and notches forming cams so that by rotation of the collars the bosses and half nut sections can be moved toward each other.

A compression spring 39 seated in counterbores in the bosses 32 yieldingly urges the same apart to maintain them in engagement with the stop collars 36 and 37.

Through the provision of this split nut arrangement the nut may be quickly engaged and disengaged with the feed screw.

To prevent feeding the miter bar into the saw and to otherwise limit the feeding, stop collars 40 are adjustably secured to the rods 13.

From the foregoing description taken in connection with the accompanying drawings, it will be readily apparent to those skilled in the art that this invention provides a practical and exceptionally handy attachment for metal cutting band saws and that the same may be used with

facility in ripping, cutting off, and mitering operations.

What I claim as my invention is:

1. A work feeding and guiding attachment for band saws and the like comprising: a bracket attachable to the work supporting table of the band saw; a pair of guideways rigidly mounted on the bracket; rods slidably received in said guideways; means rigidly connecting said rods at both ends; a miter head mounted on the means connecting the rods at one end; a work engaging face on said miter head; a feed screw journaled in the means connecting the rods and held against endwise movement with respect thereto; a hand wheel on the feed screw; and a nut carried by the bracket for engaging the feed screw so that rotation of the feed screw slides the rods and the work engaging face in a direction parallel with the axes of the rods.

2. A work feeding and guiding attachment for band saws and the like comprising: a bracket attachable to the work supporting table of the band saw; a pair of guideways rigidly mounted on the bracket; rods slidably received in said guideways; means rigidly connecting said rods at both ends; a miter head mounted on the means connecting the rods at one end; a work engaging face on said miter head; a feed screw journaled in the means connecting the rods and held against endwise movement with respect thereto; a hand wheel on the feed screw; and a nut carried by the bracket for engaging the feed screw so that rotation of the feed screw slides the rods and the work engaging face in a direction parallel with the axes of the rods, said nut being split; and means for quickly moving the nut sections toward and from each other to quickly free the nut from or engage it with the feed screw.

3. An attachment of the character described comprising: a pair of parallel rods; a cross member rigidly connecting the rods at one end; a miter head base rigidly connecting the rods at the opposite end; a miter head rotatably adjustable on said miter head base; a work engaging member carried by the miter head; a bracket in which the rods are slidably received; means for detachably securing the bracket to the work supporting table of a machine tool with the miter head base and its associated assembly slidable across the table; and means on the miter head assembly for attaching the power feed of the machine tool thereto.

4. An attachment of the character described comprising: a pair of parallel rods; a cross member rigidly connecting the rods at one end; a miter head base rigidly connecting the rods at the opposite end; a miter head rotatably adjustable on said miter head base; a work engaging member carried by the miter head; a bracket in which the rods are slidably received; means for detachably securing the bracket to the work supporting table of a machine tool with the miter head base and its associated assembly slidable across the table; and a foot on the bottom of the miter head base adapted to rest on the work supporting table to support the miter head assembly at the proper elevation.

HANS PETERSEN.
